UNITED STATES PATENT OFFICE.

HARRY MANES, OF NEW YORK, N. Y.

TOY.

1,404,132.

Specification of Letters Patent. Patented Jan. 17, 1922.

Application filed April 9, 1920. Serial No. 372,501.

To all whom it may concern:

Be it known that I, HARRY MANES, a citizen of the United States, and a resident of the city of New York, borough of Bronx, in 5 the county and State of New York, have invented a new and Improved Toy, of which the following is a full, clear, and exact description.

This invention relates to toys and has particular reference to gyroscopic aerial tops and the like.

The primary object of the present invention is to provide a highly amusing, interesting and attractive toy in which the qualities of skill, judgment and luck play proportionate parts in the operation of the same.

Another object of the invention is to provide a toy which may be utilized as an apparatus for the playing of various games in which the number of participants is unlimited as one or more persons may enjoy the sport with equal interest.

A further object of the invention is to provide a toy of the character described which is simple in construction, inexpensive to manufacture and which is strong, efficient and durable.

With these and other objects in view, 30 some of which will be more readily apparent as the nature, purpose and operation of the device is better understood, reference is made to the following description, claims and accompanying drawings forming a part 35 of this application.

In the drawings:

Figure 1 is a perspective view illustrating the operation of the same when in use.

Figure 2 is a transverse sectional view 40 through the top illustrating in dotted lines the relation of the stick when the same contacts with the peripheral guard.

Figure 3 is a similar view of a slightly modified form of the invention.

Figure 4 is a fragmentary detailed view 45 of a further modification.

Referring to the drawings by characters of reference, 10 designates a handle member such as a stick which is provided with a 50 tapered upper extremity 11. The said stick 10 may be of any formation and is not necessarily limited to the precise construction illustrated and the same is applicable to the various forms of tops illustrated in the several modifications of the invention.

Referring particularly to Figures 1 and 2 of the drawings, the top 12 comprises a head 13 which is preferably but not necessarily of substantially semispherical formation and provided with an annular flange 14. In the 60 specific construction illustrated the head 13 is provided with a reduced depending boss 15 which receives the central opening 16 of the annular flange 14 which is in the nature of a disc. The said disc like flange and head 65 13 being secured together by means of screws 17. The head 13 is provided with an axial recess 18 having an outwardly flared mouth 19 communicating with the underside of the top. The opposite closed extremity of the recess is tapered as at 20. In use and operation, the recess constitutes substantially an axial step bearing for the reception of the tapered end 11 of the stick 10 to permit of the spinning of the top thereon, the outwardly flared mouth 19 of the recess serving as a guide for the tapered extremity 11 during the operation of capturing the top after the same has been upwardly projected therefrom. In order to 70 75 provide means to minimize the chance of entirely missing and dropping the top, a depending peripheral guard is provided on the flange and as illustrated in Figures 1 and 2 of the drawing, the same is illustrated as 80 85 a ring 21 supported in spaced relation from the flange by means of the vertical depending legs 22. In operating the toy, should the player miss the outwardly flared mouth 19 in an attempt to capture the top, the 90 95 pointed extremity 11 may be manipulated in such a manner as to enter between the ring 21 and the flange 14 as illustrated by the dotted line position of the stick in Figure 2 of the drawings.

In the modified form illustrated in Figure 3 of the drawings the flange 23 is preferably dished in order that the under surface thereof will present a guide surface to increase the chance of the pointed extremity of the 100 stick entering the recess. In this form the depending peripheral guard is in the nature of an annular peripheral depending flange 24 formed integral with the flange 23. The construction of the head and recess in this 105 form is identical with the head illustrated in Figures 1 and 2. In the modified form illustrated in Figure 4 of the drawings, the flange 25 is provided with a depending peripheral guard flange 26 the free extremity 110

of which is inturned as at 27 to provide a receiving space 28 which is adapted to co-act with the tapered extremity of the stick.

In the preferred adaptation and use of the toy, the top 12 is initially associated with the stick 10 by inserting the tapered extremity 11 of the same within the recess 18, the point of the tapered extremity 11 engaging the tapered portion 20 of the recess; the stick is held in one hand, and the top is initially set in motion by revolving the same with the other hand or if desired a string may be wound around the guard member and withdrawn quickly therefrom to impart a spinning motion thereto. The operator then projects the top into the air by a quick upward movement of the stick and endeavors to capture the same as it gravitates downward by registering the tapered extremity with the recess. Should the operator miss the outwardly flared mouth 19, the stick may be manipulated in such a manner as to enter between the ring 21 and the flange 14 as illustrated in Figure 2 of the drawings. Any number of players may participate in a game in which one top is used and in which each player is provided with a stick and any rules may be formulated for the playing of various games. The top when spinning sets up a gyroscopic action which maintains the same substantially horizontal and prevents tumbling.

While there has been illustrated and described several preferred ways in which the top may be constructed, no limitation is made to the precise details of construction as variations which fall within the scope of the appended claims may be resorted to when found expedient.

Having thus described my invention, what I claim as new and desire to secure by Letters Patent is—

1. In a toy, the combination with a tapered stick of a gyroscopic aerial top adapted to be horizontally spun thereon, projected upwardly therefrom and captured thereby, comprising a head having a tapered axial recess, a circumferential flange and a depending rim constituting a guard means adapted to embrace and co-act with the ta-

pered portion of the stick to prevent dropping of the top should the pointed stick miss the recess during the capturing operation.

2. A toy including a stick having a tapered extremity and an aerial top comprising a head provided with a tapered axial recess, a circumferential flange on said head, and a depending peripheral guard member on said flange, the said recess constituting a bearing opening for the reception of the tapered extremity of the stick whereby to permit of the spinning of the top thereon and serving as a means for preventing tangential displacement during the spinning operation of the top, said recess also functioning to receive the tapered extremity of the stick during the capturing operation after the top has been vertically projected therefrom; said guard member functioning to co-act with the tapered extremity of the stick when the same misses the recess to prevent dropping of the top.

3. In a gyroscopic aerial top adapted to be initially spun upon a tapered stick, vertically projected therefrom and subsequently captured thereby, a circumferentially flanged head having a vertical bearing opening for association with the tapered portion of the stick and a depending peripheral guard member on the circumferentially flanged portion of the head adapted to receive and co-act with said stick to prevent the dropping of the top upon failure of the stick to enter the recess during the capturing operation.

4. In a toy, the combination with a stick having a tapered extremity, of a gyroscopic aerial top having a tapered axial recess constituting a bearing opening for the reception of said tapered extremity to permit of spinning of the top therein and serving as a means for preventing tangential displacement during the spinning operation, said recess further serving to receive the tapered extremity during the capturing operation, and a circumferential flange on said top having a depending guard member adapted to embrace and co-act with the tapered extremity of the stick should the same miss the recess during the capturing operation.

HARRY MANES.
